UNITED STATES PATENT OFFICE

2,431,138

SWING FOR CHILDREN AND THE LIKE

Paul M. Ressinger, Chicago, Ill.

Application September 27, 1943, Serial No. 503,928

2 Claims. (Cl. 272—54)

1

My invention relates to an improvement in children's swings. One purpose is to provide a swing or "Teeter-Tawter" which is easily set up and knocked down and which is adapted for knock-down shipment.

Another purpose is the provision of such a structure in which a minimum number of parts are employed.

Another purpose is to provide a structure in which non-critical materials are used.

Another purpose is to provide an efficient, safe, solid swing structure.

Another purpose is to provide such a structure which can be readily adjusted to take pairs of children of different weight.

Other purposes will appear from time to time throughout the specification and claims.

I illustrate my invention more or less diagrammatically in the accompanying drawings, wherein—

Figure 1 is a plan view of the assembled structure;

Figure 2 is a side elevation of the assembly structure;

Figure 3 is a section on an enlarged scale along the line 3—3 of Figure 2;

Figures 4, 5, 6 and 7 are perspective views of parts or pieces of the device.

Like parts are indicated by like characters throughout.

Referring to the drawings, 1 indicates any suitable supporting surface, 2 indicates a swing element including two vertical wood side members 3 and a connecting horizontal bottom member 4, located approximately midway of the ends of the side members 3. The member 4 is provided with a plurality of transversely extending bottom notches 5. The members 3 are connected at their ends by seat elements 6. Extending upwardly from the members 3 adjacent the seat elements but somewhat nearer the center of the board are vertical members 7 provided with cross bars 8 which the children may grasp with their hands. The members 7 may extend between the members 3 and be secured thereto by any suitable members.

10 indicates generally a pivot piece shown as having upper and lower rounded surfaces. At each side of the pivot piece is the securing block 11 vertically grooved at opposite sides as at 12. It will be observed as in Figures 3 and 7, that the member 10 is nearer one end of the blocks 11 than it is to the other to permit vertical adjustment of the height of the member 10 by merely reversing the blocks 11. The blocks are re-

2

ceived in vertical supports 14, shown as having rounded ends 15 and upper slots 16 which interpenetrate with the grooves 12 of the blocks 11. The members 14 also have bottom slots 17.

18 generally indicates a bottom cross piece having notches 19 extending transversely therethrough at two points. In communication with but out of alignment with the notches 19 are grooves 20. 21, 21 generally indicates bottom, 10 supporting members having an upwardly enlarged central portion 22 provided with a top notch 23 and a side cut-away portion 24.

In assembling the device, the two members 21 are positioned in parallel as shown in Figure 1. 15 The notches 19 of the cross member 18 slip into the notches 23 of the two members 21. The vertical members 14 are positioned with the notches 17 interpenetrating with the notches 20 of the cross member 18. The lower portion of each member 14 also seats in the cut-away portions 24 of one of the members 21. The member 10 is positioned in the notches 16 at the tops of the two vertical members 14. If the member 10 is shown in the position of Figure 7, it is at its highest adjusted position. If it is turned upside down, it is in its low adjusted position. It is received equally well in either position by the notches 16.

When the base has been assembled, the tilting board structure generally indicated as 2 is positioned on it with one of the rounded notches 5 seated on the upper rounded surface of the member 10. If the children are of the same weight, the board can be centered as shown in Figures 1 and 2. If there is a difference in the weight of the children, then the heavier children can be given a shorter length of the board 2 by merely moving the board to the right, referring to the parts in the position in Figure 2, and engaging the member 10 with another of the notches 5.

40 Although there is shown an operative form of the device, it will be realized that many changes in the form, shape and arrangement of parts might be made without departing from the spirit of this invention, and it is wished that the showing be taken as, in a sense, diagrammatic.

I claim:

1. In a swing for children and the like, a pair of parallel horizontal ground engaging side base members, each said member having a recess, intermediate its ends, on the side facing the other member, and a notch in its upper edge, a transversely extending brace having notches in its lower edge adapted to receive the notches of said side members, with the lower edges of the side members and the cross member lying in gen-

erally the same horizontal plane, two upright members each including a lower portion notched to receive and extend about said cross member and formed to seat in the side recess of one of the side members, a cross bar having a vertically grooved head at each end, said upright members being notched at the top to receive said grooved heads and a tilting board adapted to be positioned upon said last-mentioned cross member, said tilting board having a transverse groove in its lower face formed to conform to the upper surface of said cross member, the opposed surfaces of board and cross member being rounded to permit ready tilting of the board.

2. In a swing for children and the like, a pair of parallel horizontal ground engaging side base members, each said member having a recess, intermediate its ends, on the side facing the other member, and a notch in its upper edge, a transversely extending brace having notches in its lower edge adapted to receive the notches of said side members, with the lower edges of the side members and the cross member lying in generally the same horizontal plane, two upright members each including a lower portion notched to receive and extend about said cross member and formed to seat in the side recess of one of the side mem-

5
10

bers, a cross bar having a vertically grooved head at each end, said upright members being notched at the top to receive said grooved heads and a tilting board adapted to be positioned upon said last-mentioned cross member, said tilting board having on its lower surface a plurality of parallel transverse grooves, each formed to conform to the upper surface of said cross member, the opposed surfaces of board and cross member being rounded to permit ready tilting of the board.

PAUL M. RESSINGER.
